*Primary Examiner—Lucy Lieberman**Attorney, Agent, or Firm—John P. Guenther***[57] CLAIM**

The ornamental design for a bottle, as shown and described.

DESCRIPTION

FIG. 1 is an elevational view of the front of the bottle showing our new design;

FIG. 2 is a top and front perspective view thereof;

FIG. 3 is a top plan view thereof; and,

FIG. 4 is a bottom plan view thereof.

The rear and side elevational views of the bottle are the same as the front view shown in FIG. 1 except for the conventional screw threading on the bottle neck.
